ATTORNEY

UNITED STATES PATENT OFFICE

ELMER CARLSTROM, OF CHICAGO, ILLINOIS

CONCEALED WEAPON

Application filed January 2, 1932. Serial No. 584,347.

This invention relates to firearms for personal defense, and particularly to one employing either a gas or lead cartridge and which may be secured in concealed position 5 to the arm of the user and fired upon certain movements of the arm and one of the wearer's fingers.

An important object of this invention is the provision of a firearm which may be concealed beneath and within the sleeve of a garment of the wearer and be fired by movement of the wearer's finger.

A further object of this invention is the provision of a mounting element for a compact gun or the like, and having means slidably mounted thereon which, when actuated by movement of the finger, will cause the cartridge to be fired.

A further object of the invention is the provision of a weapon for self-defense which will be inexpensive to manufacture, efficient and safe in operation, and which will comprise a small number of parts.

Other and further important objects of this invention will be apparent from the disclosures in the specification and the accompanying drawing.

This invention (in a preferred form) is illustrated in the drawing and hereinafter more fully described.

On the drawing:

Fig. 1 is a top plan view of my firearm showing means whereby the same may be fastened about the arm and showing the structural features in detail.

Fig. 2 is a side elevational view taken on line II—II of Fig. 1.

Fig. 3 is an enlarged fragmentary view of the slidable rack bar and means for normally holding the same in projected position.

Fig. 4 is a cross sectional view with parts broken away showing the interior of the cartridge gun.

As shown on the drawing:

The reference numeral 10 indicates a strip of flexible leather or other similar material which is of the size adapted to pass around the fore arm of a wearer. A substantially 50 rectangular mounting plate 11 of metal hav-

ing corner apertures is secured in substantially central position on the surface of said leather strip 10 by bolts 12 which pass through the corner apertures of said mounting plate. A pair of straps having suitable 55 buckles are also secured by the bolts 12 to the mounting plate 11 and the leather strip 10 so that their central portions are beneath the leather strip 10, and the apertured ends of said straps pass through slots at one side 60 of said leather strip to be conveniently buckled on the opposite side of the fore arm, and in a position so that the gun barrel will point beneath the palm of the hand.

A metal U-shaped channel member 13 is secured by welding or the like with its back surface upon the mounting plate 11 and in a position so that its flanges 14 and 15 extend perpendicularly to said mounting plate. The flange 15 has one end thereof turned at 70 right angles to form a guard 16 for a purpose which will hereinafter appear. The portion of the upper edge of the opposite end of the flange 15 is turned horizontally and downwardly to form a housing 17 which incloses 75 spring means, as will be later described, and in which is slidably mounted one end of a slidable rack bar 18, the slidable rack bar having a horizontally extending abutment 19 at one end and having an opposite reduced end 20 about which is mounted one end of the coil spring 21 which is inclosed within the housing 17. The outer end of the housing 17 is closed except for a threaded aperture in which is threaded a screw 22 which holds the spring 21 in place and provides convenient means whereby said spring may be removed.

A gear wheel 23 having a prolonged shank 24 is rotatably mounted on the bolt 25 which passes through the mounting plate and channel member 13, and is secured at its upper end in the aperture of an ear 26 which is formed integral with the flange 15 at a point substantially midway between the ends of said flange. The teeth of the gear wheel 23 and rack bar 18 are constantly in mesh.

The manually actuatable means for rotating said gear wheel comprises a short lever 27 which is secured in a radial projecting position to the under side of said gear wheel 23. 100

A flexible cable 28 having one end secured in the aperture in the outer end of the lever 27 has its other end connected to a suitable ring 29 which is adapted to be slipped over a finger of the wearer, the flexible cable 28 being of such length so that bending of the wearer's hand at the wrist away from a substantially straight position will cause said gear wheel 23 to be rotated to slide the rack bar 16, which comprises the means for releasing a cartridge firing element which will now be described.

The cartridge exploding device which may be employed in connection with my invention 15 may be either a conventional form of gun which may be secured to the mounting plate 11, but my preferred form comprises a tubular housing 30' which has its open end internally threaded and which is secured to the 20 flange 15 and 14 by welding or the like. A metal gun barrel 31 which is bored for the conventional reception of a standard cartridge has its loading end externally threaded, whereby said barrel 30 may be threadingly 25 secured and removable from the tubular housing 30' to permit replacement of the cartridge. The gun barrel 31 is preferably of a length extending beyond the periphery of the mounting plate 11, as shown in Figs. 2 and 3.

30 A slideable metal plunger 32 having an integral centrally disposed firing pin is adapted to slide in said tubular housing 30', the slideable movement thereof being limited by a stud 33 which has one end preferably threaded 35 in perpendicular position in the slideable plunger 32, the main portion of said stud extending through and projecting above an elongated angular shaped slot 34 formed in the wall of the tubular housing 17. Said slot 40 34 terminates in a right angle to form a pronounced shoulder 35 which is adapted to engage the stud 36 to hold the plunger in retracted position, as shown in Fig. 1. A coil spring 38 is disposed between the rear end of 45 the plunger 32 and the closed end of the tubular housing 30', said spring being adapted to quickly force the plunger 32 and firing pin 37, when released, to fire a cartridge in the barrel 31.

50 It will be apparent that when loading the gun the plunger 32 will be drawn back manually by pulling backward the projecting stud 36 and engaging the same behind the shoulder 35 of the tubular housing 30'. 55 The flexible leather strip 10 comprising the sleeve is adapted to be fastened about the fore arm and secured in such position by means of a pair of leather straps 39 which have suitable buckles and apertures at the opposite 60 ends of said straps. The sleeve member 10 is fastened about the fore arm in a position so that the concealed weapon and device hereinbefore described will be on the under side of the arm and the gun buckle 31 will point 65 below the inside of the palm. The ring 29

will be slipped over one of the fore fingers and the length of the flexible cable and string 28 is such that the releasing device will be actuated to release the stud 33 to cause a cartridge to be fired only when the wearer's 70 hand will be bent backward with the palm facing forward.

It will be apparent that the wearer will bend his hand into such a position only upon a specific effort to do so, which will overcome the action of the spring 21 and cause a cartridge to be fired as hereinbefore described and in a direction toward which the wearer points his arm.

I am aware that many changes may be made and numerous details of the invention and construction thereof may be varied through a wide range without departing from the principles of this invention, and I therefore do not desire to limit the patent granted 85 thereon otherwise than necessitated by the prior art.

I claim as my invention:

1. In a device of the class described, a frame; a rack bar slidably mounted on said frame; an abutment on one end of said rack bar; a gear wheel pivotally mounted on said frame and in mesh with said rack bar; a lever secured on said gear wheel, and a cartridge exploding device mounted in said frame and having a trigger, the movement of said gear wheel being adapted to move said rack bar to release said trigger.

2. In combination with a cartridge exploding device comprising a barrel, a slideable piston and impelling spring and a trigger; a frame; a rack bar slidably mounted on said frame; a gear wheel pivoted on said frame and meshing with said rack bar; an outwardly extending lever having one end secured on said gear wheel, the rotation of said gear wheel being adapted to move said rack bar to release the trigger of said cartridge exploding device, and means to normally hold said rack bar in a projected position.

3. The combination with a cartridge exploding device comprising a barrel, a spring, a movable element adapted to stroke a cartridge; of a mounting member; a rack bar slidably mounted on said member and adapted when retracted to release said movable element; a gear wheel rotatably pivoted on said mounting member and in mesh with said rack bar; and manually actuatable means secured on said gear wheel for moving said rack bar.

4. In an automatic weapon adapted to be secured to the body of the user, a mounting member; a barrel in said mounting member adapted to retain a cartridge and having an angular slot therein forming a pronounced shoulder; a movable firing element slideable in said barrel; a spring in said barrel adapted to force said firing element to explode a cartridge; a stud secured on said firing ele-

ment and slidable in said slot, and adapted to engage said shoulder when in retracted position; a rack bar slidably mounted on said mounting member and having a transversely projecting stud, and manually actuatable means pivoted on said mounting plate adapted to move said rack bar to disengage said stud and release said firing element.

5. In an automatic weapon adapted to be secured to the body of the user, a mounting member; a barrel in said mounting member adapted to retain a cartridge and having an angular slot therein forming a pronounced shoulder; a movable firing element slidable in said barrel; a spring in said barrel adapted to force said firing element to explode a cartridge; a stud secured on said firing element and slidable in said slot and adapted to engage said shoulder when in retracted position; a rack bar slidably mounted on said mounting member and having a transversely projecting stud; a gear wheel pivoted on said mounting plate and in mesh with said rack bar, and manually actuatable means to rotate said gear wheel to move said rack bar to release said firing element.

In testimony whereof I have hereunto set my hand this 21st day of December, 1931, in

Chicago, Cook County, Illinois.

ELMER CARLSTROM.
